UNITED STATES PATENT OFFICE.

CHARLES H. GOLLER, OF HICKSVILLE, OHIO.

EXTENSION-TABLE.

No. 835,609.

Specification of Letters Patent.

Patented Nov. 13, 1906.

Application filed April 27, 1906. Serial No. 313,982.

To all whom it may concern:

Be it known that I, CHARLES H. GOLLER, a citizen of the United States, residing at Hicksville, in the county of Defiance and 5 State of Ohio, have invented certain new and useful Improvements in Extension-Tables, of which the following is a specification.

This invention relates to the art of furniture, and more particularly to extension-tables of the type which embody in their general organization one or a plurality of extension-leaves carried by the table structure and adapted to be brought into position as a part of the table-top for extension purposes or 15 withdrawn to a housed position beneath the main table-top sections at the will of the operator. To this end the invention has especially in view certain novel and practical improvements which simplify extension-tables 20 of this character and at the same time are intended to secure a positive and reliable operation in throwing the extension leaf or leaves in and out of position through the movement of the main table-sections.

25 A further object of the invention is to provide simple and practical means for automatically effecting the folding of side rail-sections for the extension-leaves through the movement of such leaves by their raising and 30 lowering mechanism. This feature provides a construction wherein the individual extension-leaves as they are thrown into position flush with the main table-top also serve to automatically swing into place side-rail sections which align with the fixed side-rail 35 members of the main table-sections.

Another object of the invention is to associate with the leaf raising and lowering mechanism a simple and effective form of latching 40 device which serves to lock the main table-sections closed and also to lock such sections against further relative movement after each extension-leaf is thrown up into operative position, thereby compelling the release of 45 the latching device before it is possible to start the movement necessary for bringing into use one of the extension-leaves.

With these and other objects in view, which will more readily appear as the nature 50 of the invention is better understood, the same consists in the novel construction, combination, and arrangement of parts hereinafter more fully described, illustrated, and claimed.

55 The essential features of the invention involved in carrying out the objects above indi-

cated are necessarily susceptible to structural change without departing from the scope of the invention; but a preferred embodiment thereof is shown in the accompanying drawings, in which—

Figure 1 is a perspective view, partially in section, of an extension-table embodying the improved extension-leaf mechanism contemplated by the present invention and showing 60 the extension-leaves in normal retracted positions housed beneath the main table-top. Fig. 2 is a bottom plan view of the table showing the parts in the positions they occupy when the extension-leaves are lifted 65 into place flush with the top of the main table section. Fig. 3 is a detail sectional view on the line 3-3 of Fig. 2. Fig. 4 is a detail view illustrating the movement of the throw-links for swinging the side-rail sections outward and inward. Figs. 5, 6, 7, and 8 are a series of similar longitudinal sectional views 70 illustrating the series of different positions assumed by the several parts of the mechanism in the operation of positioning and withdrawing one or a plurality of extension-leaves.

Like references designate corresponding parts in the several figures of the drawings.

In carrying out the present invention no 85 material change is required in the general features of construction of an ordinary extension-table, as the improvements claimed herein relate exclusively to an arrangement of one or a plurality of extension-leaves within the table-top and associated with improved leaf raising and lowering mechanism, which provides means for automatically raising the individual leaves into active position between the tops of the main table-sections, 90 and also for automatically retracting or lowering the leaves to a housed position beneath the main table-top, simply through the opening and closing movement of said table-sections. With this understanding of the general outline of the invention, there is shown in the drawings, for illustrative purposes, an extension-table, which comprises in its general organization the oppositely-arranged and matching main table-sections 1 and 2, 105 having the usual top portions 3, adapted to meet in closely-abutting relation as indicated at 4 in Fig. 1 of the drawings, when the table is closed to its normal size without the interposition of extension-leaves. The 110 said main table-sections 1 and 2 are also provided at the side edges thereof with the usual

pendent fixed side-rail members 5. The main table-framework beneath the table-top 3 is provided with the common interlocking extension slide-rails 6, which may be of the conventional type usually employed in the ordinary extension dining-table or of any approved construction which admits of the necessary relative movement of the separate table-sections 1 and 2 for extension purposes. For convenience in describing the action of the extension-table in connection with the raising and lowering of the extension-leaves therefor it may be assumed that the table-section 1 is a fixed section and the other section 2 a movable section having a movement away from and toward the fixed section for extension or shortening purposes. In this connection it is to be observed that the framework carried by the fixed table-section 1 includes stationary or fixed supporting members or bars 7, which are of sufficient length to project beyond the table-section 1 and a sufficient distance beneath the top of the movable section 2 to provide for the proper support and movement of the extension-leaves 8. One or any desired number of extension-leaves 8 may be employed, and the means for operating each leaf is the same, so where a series of such leaves are utilized in connection with the table the same are simply operated upon in succession, as will hereinafter more fully appear.

Each of the extension-leaves 8 is of a length substantially equaling the width of the main table-top, so as to form a complementary part of such top when thrown into its elevated position, and also each of said extension-leaves 8 is provided at the opposite ends thereof with the swinging inwardly-folding side-rail sections 9, which when the leaf is lowered are adapted to be folded beneath the leaf ends in an out-of-the-way position, and which when the leaf is raised to an active position are designed to be swung outward to engage with the ends of the leaf and depend therefrom in flush relation to the fixed side-rail members 5 of the main table-section 1. The said folding side-rail sections 9 are hinged at what may be termed their "upper edges," as at 10, to the under side of each leaf 8, contiguous to the ends of the latter, and the said ends of the extension-leaf are designed to register with the rabbeted ends 11^a, formed at the hinged edge of the side-rail sections, so that when such sections are moved out to an operative position the same will finish out the ends of the extension-leaf into perfect matching relation with the side edge and rail portions of the main table-sections.

The leaf raising and lowering mechanism is of the same construction and action for each extension-leaf. Referring particularly to the means for supporting and also for raising and lowering each leaf, it will be ob-

served, by reference to the drawings, that each leaf is carried by oppositely-arranged pairs of vertically-swinging carrier-links 11. These pairs of swinging carrier-links 11 of each leaf are arranged respectively at opposite sides of the transverse center to provide for the uniform support and movement of both end portions thereof. The links 11 are arranged in spaced relation and are pivoted at their lower end portions by the pivots 12 upon one side of one of the fixed supporting members or bars 7, while the upper ends of the same links are pivoted upon the upper pivots 13 to the under side of the extension-leaf 8, contiguous to the side edges 80 thereof, as may be plainly seen from the group of Figs. 5 to 8, inclusive. The links 11 for each extension-leaf swing or rock in a horizontal direction, so that the leaf 8, supported upon the upper end of the links, will 85 likewise swing or move in a horizontal direction and at the same time will always maintain its position in a horizontal plane. Furthermore, by reason of supporting the leaf 8 upon the upper ends of swinging carrier-links, said links as they swing in one direction to what may be termed their "folded position," carry the extension-leaf 8 below the plane of the main table-top, while the swinging or straightening out of the levers in the 95 other direction serves to carry and lift the extension-leaf to its elevated position in alignment and flush with the main table-top portions.

One of the carrier-links 11 of each pair of 100 said links for each extension-leaf is extended below its lower pivotal support 12 to form a rock-arm extension 14, carrying at its lower extremity a tappet-pin 15, adapted to be engaged by the reversely disposed and spaced 105 press-shoulders 16 and 17, respectively, formed on or carried by the free end portion 18 of a reciprocatory operating-bar 19. This operating-bar 19 is preferably of a spring type—that is, having a fast connection at one 110 end, as at 20, with the framework of the movable table-section 2 and having its opposite or free end portion 18 normally sprung up into an interfering path with relation to the tappet-pin 15 of the carrier-link rock-arms 14. Also 115 at its free end portion and leading off from what may be termed the "return-shoulder" 17 in contradistinction to the advance shoulder 16 the said operating-bar 19 is provided with a beveled or narrowed clearance-tongue 120 21^a, which clears the tappet-pin 15 to permit of the engagement of the shoulder 17 on the return stroke of the bar 19 during the closing-up and leaf-retracting operation.

In addition to the pin 15 each rock-arm 14 125 has offset therefrom above the plane of said pin 15 the laterally-projecting flange 21, having rounded engaging ends 22 and constituting a rocking release-cam adapted to bear downwardly upon the operating-bar 19 be- 130

tween its two shoulders for disengaging purposes, as will presently appear. In connection with these features of construction it is to be observed that a pair of the operating-bars 19 are employed, respectively, at opposite sides of the longitudinal center of the table, whereby one bar is associated with each pair of carrier-links.

For practical purposes it is preferable to associate with the features described a latching device essentially comprising a fixed catch-bar section 23, provided with a plurality of spaced catch-notches 24 and a latch-lever 25, carried by the movable table-section 2. The said latch-lever 25 is pivotally supported intermediate its ends 26 on a vertical pivot-pin, so as to permit of the horizontal rocking of said lever, and at its outer end portion the latter is provided with a spring member 27, normally pressing under tension against a fixed abutment 28 and serving to normally move the engaging point 29 at the opposite end of the lever against the fixed catch-bar 23 and into engagement with the notches 24 when said pin reaches the plane of said notches.

The outer end portion of the latch-lever 25 has connected therewith a flexible or other equivalent release-strip 30, operating as a handle for moving the outer end of the latch-lever in a direction for releasing the point 29, and thereby permitting free movement of the table-section 2, either inward or outward.

Another feature of the invention resides in associating with the folding side-rail sections 9 simple and improved means for moving such sections inward and outward. The said means consists simply in the employment of a single throw-link 31, associated with each side-rail section 9 and pivotally connected at its outer end, as at 32, to the inner side of such section and at its inner end pivotally supported, as at 33, upon the outer side of one of the fixed supporting members or bars 7. The link of each folding side-rail section 9 sets obliquely and is of greater length than the distance between such sections when swung out and the adjacent supporting member or bar 7. Hence when the extension-leaf 8 is shifted in a horizontal direction the outer end of the throw-links are moved toward or from the fixed supporting members or bars 7, with the result of automatically swinging the folding side-rail sections on their hinges.

Referring to the general operation of the table, reference need only be made to the group of Figs. 5 to 8, inclusive, of the drawings. In the first place, assume that the table is closed and the extension-leaves are lowered and housed in the positions shown in Fig. 5. To open the table and bring the extension-leaves into use, the latch-lever 25 is first released and then the movable table-section 2 drawn outward. This movement carries the advance press-shoulder 16 of the

operating-bar 19 against the tappet-pin 15 of the link rock-arm 14, with the result of throwing the links 11 upward, thereby carrying the first extension-leaf 8 into its elevated position. This is plainly shown in Fig. 6 of the drawings, and if only one leaf be used the movable table-section 2 is closed back onto the said first leaf 8 after the parts have reached the position shown in Fig. 6. With the parts in said position (shown in Fig. 6) the movable table-section 2 cannot be opened, bringing the shoulders 17 past the tappet-pin 15 on account of the point 29 of the latch-lever becoming locked in a notch 24 before such position can be reached. Hence when it is desired to also bring the second leaf into play, the latching device is held released during the opening movement, so that by a continued movement of the movable table-section the release-cam 21 will press down on the free end of the bar 19, serving to disengage the shoulder 16, and permit the said shoulder to pass on into engagement with the next succeeding tappet-pin 15, thereby repeating the same raising operation for the second leaf, bringing the latter into the position shown in Fig. 7.

To return the leaves to their retracted positions, the movable table-section 2 is first carried out to the position shown in Fig. 7 and then started on its return movement. This movement carries the return-shoulder 17 into engagement with the successive tappet-pins 15, thus causing the successive leaves to automatically withdraw one after the other without any interruption in the closing up of the table-sections 2.

From the foregoing it is thought that the construction, operation, and many advantages of the herein-described invention will be thoroughly understood without further description; but at this point it should be observed that the foregoing description, forsake of clearness, has been based on the assumption that the table-section 1 is a fixed section, while the section 2 is a movable section; but it will of course be understood that in practical construction and use of the table both of the sections 1 and 2 are necessarily movable, and the table is intended to be filled by the extension-leaves in equal proportions in each section.

It may be further observed that, if desired, leverage-assisting springs 3 may be utilized to bring the extension-leaves into position without drawing the section or sections entirely out till a notch 24 of the catch-bar is reached. In using these springs the same are connected at their opposite ends respectively to a swinging carrier-link below its pivotal point and an adjacent part of the table-framework.

I claim—

1. In an extension-table, the opposite table-sections, an extension-leaf, swinging car-

4
rier-links for said leaf having a pivotal support on a fixed member, one of said links having a tappet-pin, and a reciprocating operating-bar carried by one of the table-sections 5 and provided with reversely-arranged advance and return press-shoulders adapted to engage and disengage said pin.

2. In an extension-table, the opposite table-sections, a rising and falling extension-leaf, swinging carrier-links pivotally supported on a fixed frame member and having pivotal connection with the extension-leaf, one of said links having a rock-arm extension and a release-cam, and a shouldered operating-bar carried by one of the table-sections 15 and coöperating with said pin and cam.

3. In an extension-leaf, the opposite table-sections, a horizontal rising and falling extension-leaf, swinging carrier-links pivotally 20 supported on a fixed frame member and having pivotal connection at their upper ends with the leaf, one of said links having a rock-arm extension provided with a tappet-pin and with a rocking release-cam above the 25 latter, and a reciprocal operating-bar having a spring end portion engaged by said cam and provided with the reversely-disposed spaced shoulders coöperating with the said pin.

30 4. In an extension-table, the opposite table-sections, a latching device for said sec-

tions comprising a notched catch-bar and a spring-pressed latch-lever normally engaging the bar, said catch-bar and latch-lever being relatively shiftable, a rising and falling extension-leaf, swinging carrier-links supporting said leaf and one of which is provided with a tappet-pin and a release-cam, and a reciprocal operating-bar having separate press-shoulders coöperating with said pin. 35 40

5. In an extension-table, the opposite table-sections, a rising and falling extension-leaf, swinging side-rail sections hinged to the end portion of the leaf, single throw-links 45 interposed between the side-rail sections and a point of fixed support, and leaf raising and lowering mechanism.

6. In an extension-table, the opposite table-sections, a rising and falling horizontally-movable extension-leaf, swinging side-rail 50 sections hinged to the end portions of the leaf, a single throw-link interposed between, and having hinged connection, respectively with, the side-rail sections and a fixed support, and leaf raising and lowering mechanism. 55

In testimony whereof I hereunto affix my signature in the presence of two witnesses.

CHARLES H. GOLLER.
